[57] ABSTRACT

A can with an extensible pouring spout of plastic which is displaceable in a mouthpiece from a recessed

position. The spout has a flange located on its upper end and is carried pendent in the can, to a pouring position projecting from the can in which it is kept by engagement of a securing part of the spout with a flat counterpiece on the mouthpiece. The securing part is formed by a mainly conical extension of the cylindrical side wall of the spout at the lower end of the spout, to which spout belongs a sealing plug of plastic for tight sealing of the upper open end of the spout. The sealing plug has a finger grip bendable thereinto and outside of circumferential projections or grooves for engagement with matching inside projections or circumferential grooves inside the spout. The can is particularly characterized in that dependable finger grip of the sealing plug branches off centrally from a central, membrane-like part of the bottom of the depression of the sealing plug, a plate part over one side of the depression, in order that the upper, outermost end of the finger grip may join firmly in the sealed position of the sealing plug in such a manner that the innermost end of the finger grip presses the central, membrane-like part of the bottom down, bulging like a spherical shell and pressing, thereby, by pushed-in pouring spout, a lower edge part projecting from the lower peripheral part of the sealing plug against the cylindrical part of the pouring spout, same pressing a circumferential bulge out for tight contact against the lower edge part of the mouthpiece of the can, the projecting lower edge part of the sealing plug extending downwards in front of a circumferential bead in the pouring spout, when a projecting flange rests on the upper flange of the spout, when this upper flange is resting on the mouthpiece of the can.

**CAN WITH AN EXTENSIBLE POURING SPOUT
WITH SEALING PLUG**

The present invention relates to a can with an extensible pouring spout of plastic, which is displaceable in a mouthpiece from a recessed position, in which the spout by means of a flange located on its upper end is carried pendent in the can, to a pouring position projecting from the can in which it is kept by engagement of a securing part of the spout with a flat counterpiece on the mouthpiece, the securing part being formed preferably by a mainly conical extension of the cylindrical side wall of the spout at the lower end of the spout, to which spout belongs a sealing plug of plastic for tight sealing of the upper open end of the spout, which sealing plug has a finger grip being bendable into the same and outside circumferential projections or grooves for engagement with matching inside projections or circumferential grooves inside in the spout.

Object of the invention is to provide a pouring spout with a sealing plug of the kind which is particularly easy to handle without getting into touch with the contents of the can and without getting messed up with this contents, e.g. oil, merely by pulling the finger grip of the sealing plug for extraction and opening of the pouring spout for pouring out the material from the can and merely by pressing the finger grip for pushing-in of the pouring spout and sealing of the same with the sealing plug, the whole time with tight sealing of the pouring spout against the mouthpiece of the can.

This object is according to the invention mainly achieved by the fact, that the bendable finger grip of the sealing plug branches off preferably centrally from a central, membrane-like part of the bottom of a depression in the sealing plug, a plate part over one side of the depression in order that the upper, outermost end of the finger grip may join firmly in the sealed position of the sealing plug in such a manner, that the innermost end of the finger grip presses the central, membrane-like part of the bottom down, bulging like a spherical segment shell and pressing thereby, by pushed-in pouring spout a lower edge part, projecting from the lower, peripheral part of the sealing plug against the cylindrical part of the pouring spout, same pressing a circumferential bulge or bead out for tight contact against the lower edge part of the mouthpiece of the can, the projecting lower edge part of the sealing plug extending downwards in front of a circumferential bead in the pouring spout when the upper flange of the spout rests on the upper flange of the pouring spout, when this flange is resting on the mouthpiece of the can.

Thereby the pouring spout is tightly sealed in the mouthpiece of the can and countersunk in the depression in the top plate of the can.

By displacement of the uttermost end of the finger grip so that it will be free of the plate part over the one side of the depression in the sealing plug and by pulling then upwards the finger grip, the sealing plug may be pulled upwards in the pouring spout, pulling at the same time the latter up or out for pouring position, the projecting lower edge part of the sealing plug will hit the inside beads of the pouring spout. By further pulling the finger grip the sealing plug can be pulled out beyond the upper bead with the pawl-like cross-sectional shape and out of the pouring spout ready for pouring out the material from the can.

After the pouring out, the pouring spout and the sealing plug may be pushed back to the sealing position merely by pressing the finger grip.

The invention will be further explained below with reference to the drawing, in which

FIG. 1 shows part of a can with mouthpiece and with an embodiment of a pouring spout with a sealing plug according to the invention, in vertical section,

FIG. 2 parts of same, seen from above,

FIG. 3 same parts, but with some of them in an other position, in vertical section, and

FIG. 4 same parts in pouring position and with removed sealing plug, in vertical section.

A can 1 has a top plate 2 with a depression 3 with a bottom 4 with a bent part 5 with a turned down, cylindrical edge part 6 as a mouthpiece round a hole in the bottom 4. The edge part 6 has an outwards bent and flat counterpiece 7.

A tube shaped part 8 of a mainly tube shaped pouring spout 9 fits roughly into the mouthpiece or the cylindrical edge part 6 and has at foot a conical extension 10 as a securing part, which by extracted spout 9 to the position shown in FIG. 3 or 4, the pouring position, wedges tightly to the mouthpiece 6, as a low, projecting lower edge part 11 of the spout 9 then forms a stop against the flat counterpiece 7 of the mouthpiece 6.

At the top the spout 9 has an outwards projecting flange 12 with a part 13 projecting further to one side as a pouring spout and inside beads 14 and 15. The bead 14 has a triangular, pawl-like cross-sectional shape and the bead 15 has a semi-circular cross-sectional shape. Between the beads 14 and 15 there is an inside circumferential groove 16 at top and inside the spout 9.

A rather flat sealing plug 17 has an upwardly open cavity or depression 18 with a bottom 19, from the central dome-shaped outwardly convex membrane-like part 20 of which branches off a bendable finger grip 21 with outside pawl-like projections 22. At one side the sealing plug 17 has over the depression 18 a plate part 23 flushing with an outwards projecting flange 24 on the sealing plug. In the sealing position of the plug 17 shown in FIG. 1 the outermost end of the finger grip 21 is wedged in under the plate part 23. Thereby the innermost end of the finger grip 21 presses the central part 20 of the bottom 19 of the plug bulging downwards as a spherical segment, whereby an outside lower edge part 25 of the sealing plug 17 presses a circumferential bulge or bead tightly out under the flat counterpiece 7 of the mouthpiece 6, the flange 24 then resting on the flange 12, which rests on the annular part 5 of the top plate 2 and the flange 24 and the entire plug 17 are countersunk in the depression 3 of the top plate 2.

By pressing the finger grip 21 sideways same is released from the plate part 23, so that one may by gripping the finger grip 21 pull up the sealing plug 17 into the position shown in FIG. 3, in which its bottom part is pulled up with its central dome-shaped outwardly convex membrane-like part 20 bulged as a spherical segment shell and the lower edge part 25 up into the groove 16 while the spout 9 is at the same time pulled up into the position shown in FIG. 2, with its conical extension 10 pulled up for tight contact in the mouthpiece 6 and its lower edge part 11 pulled up for contact with the flat counterpiece 7 of the mouthpiece.

By further pulling the finger grip 21 the sealing plug 17 may be pulled quite up from the spout 9, and the can

1 with the spout 9 can be tilted for instance into the position shown in FIG. 4 for pouring out the material not shown from the can.

By opposite operations in opposite succession the spout 9 can be pressed down into the can 1 and the plug 17 be pressed down into the spout 9 and the finger grip 21 be pressed down into the depression 18 to the sealing position shown in FIG. 1. This may be made merely by pressing the finger grip 21, while opening may be effected merely by pulling the finger grip 21. Above the latter may be glued a label 27 on the top plate 2 with e.g., the following instructions: Push out the finger grip — pull up plug and pouring spout — pull off plug — pour out material from can — after pouring — press pouring spout, plug and finger grip on place in sealing position. These operations may be made again and again without getting pouring material e.g., oil on your fingers. At the top part 8 of the pouring spout there is an air equalizing hole 28.

We claim:

1. A can comprising an extensible pouring spout of plastic, which is displaceable in a mouthpiece of the can between a recessed position, in which the spout hangs within the can from a flange located at its upper end and a pouring position projecting from the can, in which it is kept by engagement of a securing part of the spout with a flat counterpiece on the mouthpiece, the securing part being formed by a conical extension of

the cylindrical side wall of the spout at the lower end of the spout, a sealing plug of plastic for tight sealing of the upper open end of the spout, the sealing plug having a finger grip bendable thereinto and external 5 circumferential projections or grooves for engagement with matching internal projections or grooves in the spout, characterized in that the bendable finger grip of the sealing plug extends centrally, from a central dome-shaped outwardly convex membrane-like part of the 10 bottom of a recess of the sealing plug, a plate part extends over one side of the recess to hold the upper, outermost end of the finger grip downwardly bent in the retracted position of the spout and in the sealed position of the sealing plug in such a manner, that the innermost end of the finger grip presses the central, membrane-like part of the bottom down, whereby a lower edge part projecting from the lower peripheral part of the sealing plug is forced against the cylindrical part of the pouring spout, and forms a circumferential bulge or bend in tight contact against the lower edge part of the mouthpiece of the can, the projecting lower edge part of the sealing plug extending downwardly beyond a circumferential bead in the pouring spout, when the upper flange of the plug rests on the upper flange of the spout, while said upper flange of the spout is resting on the mouthpiece of the can.
